GRIPPER BAR MECHANISM

Alexander J. Albrecht, West New York, N. J., assignor to R. Hoe & Co., Inc., New York, N. Y., a corporation of New York

Application March 26, 1947, Serial No. 737,236

6 Claims. (Cl. 101—409)

1

This invention relates to printing machines and more particularly to sheet fed machines of the flexible conveyor type.

A sheet fed printing machine of the flexible conveyor type, and to which the present improvements may be applied, is fully described in Huck Patent 2,231,914. As there disclosed, the successive sheets are carried through the printing units by gripper bars having a number of gripper elements or jaws which open and close to receive a sheet at the registering unit and discharge a sheet at the delivery, but which remain closed during the passage of the sheet through the successive printing units.

One object of the present invention is to provide an improved gripper bar and mechanism for opening and closing the gripper elements thereof.

A further object of the invention is to provide an improved device for holding a sheet adjacent its corners.

With these and still other objects which will appear in the following full description in mind, the invention consists in the combinations and arrangements of parts and details of construction which will now first be fully described in connection with the accompanying drawing and then be more particularly pointed out in the appended claims.

In the drawing:

Figure 1 is a cross section through a gripper bar and parts of a registering cylinder;

Figure 2 is a plan view of one end of the gripper bar of Figure 1;

Figure 3 is a plan view on a reduced scale of one end of the gripper bar and registering cylinder;

Figure 4 is a detail view showing an attachment employed for holding down a sheet corner; and

Figure 5 is a section on the line 5—5 of Figure 4.

The invention relates to the gripper bar and the mechanism employed for opening and closing the jaws thereof. The other press elements and their operation and cooperation with the gripper bar are well known in themselves, being fully described in the Huck patent above referred to and, accordingly, are not shown herein.

Figure 1 shows a portion of a registering cylinder

2

having a recess 2 in which the gripper bar 3 is received. As will be well understood by those skilled in the art, the gripper bar will be seated in the recess 2 at a proper point in the rotation of the registering cylinder and the mechanism within and associated with the cylinder will operate to open and close the jaws of the gripper for receiving and grasping a registered sheet. Heretofore, and as shown in the Huck patent, the gripper bars have comprised a plurality of elements extending longitudinally of the registering cylinder and to which a relative movement is imparted for the purpose of controlling the action of gripper jaws associated therewith. Such elements have taken the form of telescoped tubes, one jaw of each gripper being carried by an outer tube, and the other by the inner tube, so that relative movement of these tubes causes the jaws to open and close. Such a construction is relatively heavy, complicated and bulky and the action of the registering cylinder upon the gripper bar may have a tendency to unseat the gripper bar.

The gripper bar of the present invention comprises a single longitudinally extending element in the form of a tube 4 which carries a number of gripper elements 5 spaced along its length at suitable intervals. Each gripper element 5 comprises a frame 6 which is fastened to the tube 4 as by means of the screws 7 and upon which is formed an inner or lower jaw 8 of a pair of gripper jaws. The outer or upper jaw 9 cooperating therewith is carried by a lever 10 which is slotted as indicated to fit around the frame 6 and pivotally mounted thereon by a shaft 11. Swinging the lever 10 counterclockwise about shaft 11 separates or opens the jaws 8 and 9, while swinging it clockwise into the position of the figure causes the jaws to close for grasping a sheet. The lever 10 is operated by a poppet bar 12, one end of which is connected to the inner or lower end of the lever 10 by a link 13, having forks at each end which are pivotally connected to the rod 12 and lever 10. The tube 4 has opposed apertures 14 and 15 for accommodating the poppet rod 12 and associated elements. The aperture 14 receives a thrust member 16 which surrounds the rod 12 and within which the rod 12 slides, while the aperture 15 is threaded and receives a correspondingly threaded thrust member 17, also hav-

ing a central aperture through which the rod 12 slides. A washer 18 is fastened to the rod 12 and inner and outer springs 19 and 20 are interposed between the washer 18 and thrust member 16. The spring pressure holds the thrust member 16 in the position shown, in which a peripheral flange thereon seats in a counterbore in the inner surface of the tube 4, as indicated, tending to force the washer 18 against the fixed thrust member 17. A sheet of paper between the jaws 8 and 9 will be held firmly thereby due to the action of the springs 19 and 20 and washer 18 will be slightly spaced from the thrust member 17 under such conditions. As will be apparent, a definite gripper pressure is thus obtained by each gripper 5, and this pressure will not be influenced by the action of any of the other grippers 5.

The gripper bar is located in a definite position in the registering cylinder by rollers 21 rotatably mounted on a plate 22 fastened to the registering cylinder and cooperating with bearer rings 23 toward the ends of the gripper bar. At each end of the gripper bar there is fastened an end frame assembly 24 carrying a roller 25 which cooperates with an upper cam track, the surface of which is indicated by the phantom line 26, for holding the gripper bar firmly down against the rollers 21. The end frame assemblies 24 carry also rollers 27 and 28 for positioning the gripper bar in cylinder 4, in the manner shown in the Huck patent. A flexible conveyor in the form of a sprocket chain 29 at each end of the gripper bar serves to carry the bar to and from the various units in the usual way.

The various grippers 5 are operated by a series of fingers 30 carried by a shaft 31, which is journaled in the registering cylinder 4 and one end of which carries an arm 32 and cam follower roller 33, indicated in phantom in Figure 1, the roller 33 following a stationary cam 34 affixed to the frame and a portion of which is also indicated in Figure 1. The solid line position of the fingers 30 in the drawing of Figure 1 is an intermediate position in which the fingers are just engaging the poppet rods 12 for opening the jaws 8 and 9. A box cam 34 is designed to move the fingers 30 into a more outward position indicated by the phantom line 30' for providing space for the insertion and removal of the gripper bar and into a more inward position, indicated by the phantom outline 30² for pressing the poppet rods 12 to open the gripper jaws. The operation of the cam and the control of the times of opening and closing of the gripper bar jaws may be the same as in the Huck patent referred to.

With the sheets of certain sizes it may happen that a sheet, when in laterally registered position, will extend sufficiently far beyond the last gripper element of the series which engages its forward end so as to create a possibility of the free corner of the sheet turning upwards and becoming bent so as to spoil the appearance of the sheet and interfere with the printing action. For holding down such a free corner, there is provided an attachment in the form of an offset finger 35 mounted on an extending end 36 of the shaft 11 associated with the gripper in question. The finger 35 is held on shaft 11 by screw 37 and is coupled to the movable jaw 9 by means of a pin 38 so as to move therewith. The finger 35 will not grip the sheet but will hold its corner down on the cylinder.

It will be understood that while a shaft 31 with its gripper operating fingers 30 and cam roller 33 is herein shown only in connection with a

registering cylinder, such as the cylinder 13 of Patent 2,231,914, it is also used on a discharge cylinder that passes the sheets to a delivery such as the transfer chain 29 of the machine shown in the patent. In that machine, each of the gripper bars, of which there are nineteen in a four-unit machine, is provided with gripper operating mechanism, whereas with the improved gripper bar herein disclosed, gripper operating mechanism is required only on the registering cylinder and on the discharge cylinder.

What is claimed is:

1. In a sheet fed printing press of the type having a plurality of gripper bars carried through the press by conveyor chains, and in combination, a gripper bar comprising a tubular supporting member having a plurality of aligned transverse bores spaced along its length, a fixed gripper jaw and movable gripper jaw adjacent each said bore, and an operating rod slidably mounted in each bore, connected at one end to the adjacent movable jaw and spring pressed to hold the same in sheet gripping position against the fixed jaw, the opposite ends of the said operating rods extending outwardly from the said tubular supporting member for pressing said rods inwardly against the action of the springs to open the gripper jaws, and a registering cylinder having means for receiving and holding the gripper bar through a predetermined angle of rotation of the cylinder, and a member mounted in the registering cylinder and movable with respect to it for pressing the said rods of the gripper bar, when so held, inwardly to open the gripper jaws.

2. In a sheet fed printing machine, and in combination, a plurality of grippers for receiving and holding the leading edge of a sheet and comprising lower jaws and cooperating upper jaws movable with respect thereto for gripping and releasing a sheet, and means operable with said grippers and located beyond the grippers for holding down the corner of a sheet, the mechanism being constructed and arranged to provide a space under the corner of the sheet when held down by the last said means.

3. In a sheet fed printing machine, a gripper bar comprising a supporting member and a plurality of grippers spaced therealong, and means also carried by said gripper bar, located beyond said grippers and operable with said grippers for holding down the corner of a sheet upon a registering cylinder, the gripper bar being constructed and arranged so as to leave a space under the corners of the sheet when so held down by the last said means.

4. In a sheet fed printing machine, a gripper bar comprising a supporting member and a plurality of grippers spaced therealong, each gripper comprising a fixed jaw and a movable jaw and means also carried by said gripper bar beyond the grippers and movable with a movable gripper jaw for holding down the corner of a sheet upon a registering cylinder, the gripper bar being constructed and arranged so as to leave a space under the corner of a sheet when so held down by the last said means.

5. In a sheet fed printing machine, a gripper bar comprising a supporting member and a plurality of separately operable grippers spaced therealong, and means also carried by said gripper bar beyond said grippers and operable with said grippers for holding down the corner of a sheet upon a registering cylinder the grippers being constructed and arranged so as to

leave a space under a corner of a sheet when so held down by the last said means.

6. In a sheet fed printing machine, a gripper bar comprising a supporting member and a plurality of separately operable grippers spaced therealong, each gripper comprising a fixed inner jaw and movable outer jaw, and means also carried by said gripper bar beyond the grippers and operable with the movable jaw of one of said grippers for holding down the corner of a sheet upon a registering cylinder, the gripper bar being constructed and arranged so as to leave a space under the corner of a sheet when so held down by the last said means.
